RAYMOND MAZELLI, OF BELLAIRE, OHIO, ASSIGNOR OF ONE-HALF TO R. MATTUCCI,
OF BELLAIRE, OHIO.

RIM-BREAKER.

1,370,698.

Specification of Letters Patent.

Patented Mar. 8, 1921.

Application filed November 1, 1919. Serial No. 334,923.

To all whom it may concern:

Be it known that I, RAYMOND MAZELLI, a citizen of the United States of America, and resident of Bellaire, county of Belmont, and 5 State of Ohio, have invented certain new and useful Improvements in Rim-Breakers, of which the following is a specification.

This invention relates broadly to rim-tools, and more particularly to an opening 10 and closing tool for demountable tire rims.

The primary object of this invention is to provide a simple and efficient device whereby the split demountable rims commonly employed for mounting pneumatic tires may 15 be quickly and easily opened and closed.

With this and other objects in view, the invention resides in the features of construction, arrangement of parts and combinations of elements which will hereinafter 20 be fully described, reference being had to the accompanying drawings, in which—

Figure 1 is a central longitudinal section of the invention, illustrating the application thereof;

Fig. 2 is a section on line 2—2, Fig. 1, and Fig. 3 a top plan view of one of the rim-gripping devices.

Referring to said drawings, in which like designating characters distinguish like parts 30 throughout the several views—

1 indicates two similar aligned screw members which are connected by a turnbuckle 2 whereby relative adjustment thereof may be effected. Each of said screw members has 35 its outer end connected by a pivot-pin 3 to the parallel tail portions 4 of a jaw which is generally designated by the numeral 5 and which is pivotally mounted upon a transverse shaft 6. Said shaft has a vertically 40 disposed pin 7 rigidly mounted in each of its opposite ends, and pivoted upon the opposite projecting ends of each of said pins 7 are inwardly directed lugs 8 carried by the upper and lower edges of a plate or bar 45 9, said lugs being located intermediate the ends of said bar.

This jaw 5 is formed of a single piece of sheet metal and is approximately of U-shape in cross section with the parallel 50 members thereof mounted upon said shaft 6 below and slightly forward of the pivot pin 3. The front, or outer, end of said jaw is constituted by a transverse wall 5^a which is inclined somewhat with respect to the longitudinal axis of the jaw and which has its

outer face toothed or otherwise roughened for engagement with the inner annular surface of the demountable rim, as 10, which is to be acted upon.

The oppositely disposed bars 9 have 60 formed on their confronting faces at or adjacent to their outer ends laterally disposed heads or jaws 11, the rearwardly facing walls of which are provided with teeth 12, or are otherwise roughened, said jaws 11 being 65 adapted to engage the outermost surfaces of the opposite clencher-beads or flanges 13 formed on said rim 10, so as to coact with the jaw 5 for engaging the interposed rim in a vise-like grip.

In practice, following the placing of the jaws 5 in seating relation to the inner peripheral surface of the rim 10, the outer ends of each pair of bars 9 gravitate downward to points wherein the jaws 11 thereof 70 seat upon the beads 13 at points approximately opposite to the adjacent jaw 5. An adjusting screw 14 carried by the inner end of one of said bars 9 is adapted to be adjusted to cause its end to exert pressure 75 against the confronting face of the corresponding end of the opposite bar whereby the outer ends of said bars are forced toward each other over the opposite beads 13 of the rim. In this position the device is 80 securely attached to the rim. Then, as is obvious, rotation of the turnbuckle 2 for drawing the screw members 1 toward each other, not only rocks the jaw 5 on the shaft 6, as on a fulcrum, for increasing the gripping force applied, but also serves to contract the rim by drawing the ends of the split rim past each other in a manner which is obvious. On the other hand, following the application of a tire to the collapsed 85 rim, rotation of the turnbuckle in a direction separating the screw members obviously results in said rim being forcibly expanded to restore the ends thereof to their normal relationship.

What is claimed is—

In a rim breaker, a pair of rods, a turnbuckle connecting the rods, jaws having spaced tail parts receiving and pivoted to the outer ends of the rods, a transverse 105 shaft carried by each jaw and having its ends extending beyond the sides of the jaw, bars having spaced lugs between their ends receiving the shaft ends in the space between the lugs, pivot pins extending trans- 110

versely through the shaft ends and through the lugs, the outer ends of the bars having inturned lips extending in front of the respective effective end faces of the jaws, and a screw between the inner ends of the bars for moving the latter about their pivots, each screw extending substantially parallel with the shaft and transverse to the

respective rods so as to engage the same and limit the tilting of the bars in one direction. 10

In testimony whereof I affix my signature in presence of two subscribing witnesses.

RAYMOND MAZELLI.
